UNITED STATES PATENT OFFICE.

JOHANN SCHULER, OF DUSSELDORF, GERMANY.

RAIL-FASTENING TO SLEEPERS.

1,183,682.

Specification of Letters Patent.

Patented May 16, 1916.

Application filed September 22, 1913. Serial No. 791,097.

To all whom it may concern:

Be it known that I, JOHANN SCHULER, of Dusseldorf, Germany, a subject of the German Emperor, have invented a new and useful Improvement for Rail-Fastenings to Sleepers, of which the following is a specification.

This invention relates to a hook-nail for fastening rails on sleepers, consisting of one part only having a springy or elastic neck and head.

Rail fastenings with springy or elastic cramp-irons and springy or elastic holding portion are known. So are rail fastenings and hook nails which have a special elastic part between head and foot of rail, constructed in such a way as to prevent a loosening of the hook nails in the sleepers.

All the aforesaid rail fastenings have the disadvantage that each and every one consists of two parts *i. e.* of a springy or elastic part and a fixed or rigid part (screw, wedge, hook nail) to fix the springy or elastic part in position. This disadvantage prevents simpleness in construction and maintenance and consequently lowers the traffic safety. The two part-construction makes them unnecessarily expensive.

A springy or elastic rail fastening can be constructed much cheaper, reliable and handy if the springy or elastic and the fastening part are combined in one piece. This simplification has been achieved by making the head and neck of the hook nail springy or elastic. The elasticity of the neck of the rail is gained by a suitable elongation or by suitable breasting or molding; the elasticity of the head by a doubled bending.

Figure 1 shows a side elevation of the preferred form of rail nail according to the present invention. Fig. 2 is a cross section thereof. Fig. 3 is a side elevation of the rail

having a modified form of neck. Fig. 4 is a cross section thereof.

The elasticity of the head of the nail (b) is caused by a double bending of the head of the nail.

The rail nail according to the present invention consists of a shank *a* having a pointed end and a contact point *d* formed at the opposite end bent at right angles to said shank while the intermediate portion *b* is bent back and forward on itself and adapted to form a resilient base for the contact point. In the modified form of rail nail, Fig. 3, the portion *b* is shown to be somewhat flatter than that shown in Fig. 1.

The improvement of this rail-fastening-hook-nail is, that the medium of fastening consists of one part only which has by proper arrangement an elastic or springy neck and head and causes an elastic pressure on the rails direct, without any intermediate parts, thus causing an important simplicity and cheapness of construction and insuring an easy handling and maintenance, making a loosening of the nails in the sleepers impossible.

Having thus fully described my invention what I claim as new, and desire to secure by Letters Patent of the United States is—

A rail nail composed of a shank including its pointed end, a contact point formed at the other end thereof bent at right angles to said shank, the intermediate portion bent back and forward on itself adapted to form a resilient base for said contact point, substantially as described.

In witness whereof I have hereunto set my hand in presence of two witnesses.

JOHANN SCHULER. [L. s.]
